Joseph T. Bedford.

UNITED STATES PATENT OFFICE.

JOSEPH T. BEDFORD, OF NEW YORK, N. Y.

PROCESS OF WAXING PAPER.

SPECIFICATION forming part of Letters Patent No. 273,013, dated February 27, 1883.

Application filed June 20, 1882. (No model.)

To all whom it may concern:

Be it known that I, JOSEPH T. BEDFORD, of the city, county, and State of New York, have invented certain new and useful Improvements 5 in the Process of Waxing Paper, of which the following is a description in such full, clear, concise, and exact terms as to enable any one skilled in the arts to which my invention belongs, or with which it is most nearly connected, to make and use the same, reference being had to the accompanying drawing, making part of this specification, and to the letters and figures of reference marked thereon.

This invention does not embrace anything 15 novel in machinery, but consists of a novel method of treating the paper, in combination with the operation of waxing it with paraffine or other similar material.

The drawing is all combined in one figure, 20 and shows the machinery by which the invention is accomplished.

In waxing paper it is desirable to use as little wax as possible to accomplish the desired result, and at the same time to get it evenly 25 distributed and thoroughly impregnated in the paper, and yet leave as much as possible on the surface in the form of a hard, uniform gloss. To accomplish this result it is necessary to raise and maintain the wax and waxing-rollers and 30 machinery to as high a temperature as possible, having due regard to the nature of the material and object sought to be accomplished, and then to suddenly cool the waxed paper to as low a 35 temperature as possible the instant it leaves the heating machinery.

The drawing illustrates a printing and also a cutting attachment; but these attachments do not make any part of the subject-matter of this specification, but may form the subject of 40 a separate patent. They are illustrated and described here merely to show their relation to the invention proper.

Reference being had to the drawing, A is a roll of paper; B, an idle-roller; *cc*, guide-rollers; D, type-cylinder; E, pressure-cylinder; F, ink-reservoir; G *h*, inking-rollers; *i*, guide-rollers; K, heating-rollers; J, J, waxing-rollers, also heated; A' A', reservoirs for coating with wax, also heated; *dd*, brushes for spreading 45 the wax on the paper; V, closed chamber for containing the waxing and heating devices; L L, coils of steam-pipe; N, cooling-chamber;

M, pipes through which a blast of cold air is forced into the cooling-chamber upon both sides of the paper; o, a roller to carry the paper 55 through the cooling-chamber; P, guide-rollers; Q, a roller in which a series of creases are cut, into which the rotating knives R work to cut the paper longitudinally; S, a roller over which the paper passes, and upon which it is cut 60 transversely by a knife, b, working in the slits *a* of the roller. T and U are receiving-tables upon which the paper is laid as it is cut upon the roller S.

The course of the paper through the print- 65 ing-machine, the waxing-machine, the cooling-chamber, and the cutting and receiving machine is indicated by the dotted line.

There are none of the parts that, considered by themselves, possess any novelty. The in- 70 vention is in the combination and treatment of the paper. The wax is spread upon the paper by the same means and in the same manner sub- 75 stantially as in my patent dated February 28, 1882. The point of the invention is the heat- 75 ing of the paper and wax during the operation of waxing to its maximum in the practice of the art and maintaining its temperature until it leaves the heating media, and of then sud- 80 denly reducing its temperature by bringing it in contact with an atmosphere of low temper- 85 ature. This is done by inclosing the heating and waxing apparatus within a closed cham- 85 ber, V, and by combining with it a cooling- chamber, N, through which a blast of cold air 90 is continually passing. The blast of air is ob- 90 tained by means of a blower or an air-com- 95 pressor connected to the pipes M. The most effectual way of obtaining the desired degree of cold is by the use of an air-compressor ar- 90 ranged to deliver directly into the cooling- chamber through the pipes. By raising the temperature of the paraffine as high as possi- 95 ble without vaporizing it, and then suddenly cooling it artificially, the paper can be run rap- 95 idly through the waxing apparatus, where only a small amount of wax will be taken up com- 95 paratively, and a hard, uniform surface will be left upon the paper, the improvement thus sav- 100 ing time and material and producing a superior article.

I am aware that in waxing paper it has been proposed to pass the paper over hot rollers in the open atmosphere and afterward under a

blower; but in that plan only one side of the paper is affected by the blower, there is no way of confining the cold air upon the paper, the reduction of temperature is not sufficient, and the cooling is not sudden enough. The point is to suddenly cool the waxed paper by passing it from a hot chamber into and through a cold one, as above described and illustrated.

- 5 What I claim, therefore, is—
10 The method, substantially herein described, of treating paper in the process of waxing it,

which method consists of first passing the paper over heating and waxing rollers confined in a heated chamber, and of then suddenly cooling it by passing it directly from the heated chamber into a chamber of low temperature, substantially as described, for the purpose specified. 15

JOSEPH T. BEDFORD.
